ATTORNEYS

UNITED STATES PATENT OFFICE.

JOSEPH HIRSHSTEIN, OF CLEVELAND, OHIO.

INSERT AND HOLDER FOR CONCRETE FORMS.

Application filed August 7, 1924. Serial No. 730,589.

To all whom it may concern:

Be it known that I, JOSEPH HIRSHSTEIN, a citizen of the United States, residing at Cleveland, in the county of Cuyahoga and 5 State of Ohio, have invented a certain new and useful Improvement in an Insert and Holder for Concrete Forms, of which the following is a full, clear, and exact description, reference being had to the accompanying drawings.

This invention is concerned with the construction of concrete forms and more particularly to concrete forms to which it is desired to attach inserts comprising wall 15 or ceiling anchors for pipes and the like.

The general object of my invention is to provide an insert adapted to become a permanent part of the concrete structure and which may be attached to the concrete form 20 at the desired position and be maintained in that position during the pouring of the concrete and which will not impede in any manner the removal of the concrete form from the concrete.

More specifically my invention is directed 25 to the provision of an insert retaining device which may be attached to the form separately of the insert and to which the insert may be readily attached and be retained 30 thereby, the retaining device being such that it will readily disengage from the insert when the form is being removed.

Other objects of my invention will hereinafter be set forth in the following description 35 which refers to the accompanying drawings illustrating a preferred form thereof and modifications of this preferred form.

The essential characteristics are summarized in the claims.

In the drawings I show in cross-section in Figs. 1 and 2, an insert placed in engagement 40 with a retaining member secured to the form. In Figs. 3 and 4, I show in cross-section the insert illustrated in Figs. 1 and 45 2, but engaged and maintained in position by a modified form of the retaining means shown in Figs. 1 and 2; in Fig. 5 I show in perspective a preferred form of insert retaining means, the insert illustrated being 50 the same as the insert shown in Figs. 1 to 4: Fig. 6 shows the insert retaining means illustrated in Fig. 5 as being attached to

a member of the form, the relation of the insert being outlined by the dot and dash lines.

My invention may be embodied in a variety of simple forms and as disclosed in the present application, it is particularly adapted to retain an insert, such as I have disclosed in my Patent No. 1,475,342 issued 60 to me November 27, 1923. Such an insert comprises a hollow metallic structure, preferably a casting having a flanged base 10, converging side walls 11 and converging end walls 12 whereby it becomes locked in 65 the concrete when the latter is once set. Formed interiorly of the casting are intermediate ribs 13 properly spaced to support the head of a bolt with the shank thereof extending through the open side of the insert. Adjacent the open side of the insert, I also provide similarly formed ribs 14 for engaging the head of a bolt provided with a shorter shank. It will be noted from 70 the drawings that both sets of ribs do not extend the full length of the insert but terminate short of the end walls to permit the head of the bolt to be passed into the insert and over the ribs, the sets of ribs being formed in staggered relation, whereby a bolt may be positioned in any desired 75 location within the confines of the four walls of the insert.

Various expedient methods have been resorted to, to position inserts of this and other types upon the concrete form, by the use of nails, for instance, which were driven into the form in juxtaposition to the outer surfaces of the walls of the insert; also by providing apertured lugs or holes in flanges 80 through which nails could pass into the form. These methods have been effective in maintaining the insert in the desired position while the concrete is being placed in the form, but it frequently occurs that the concrete chips or cracks when the members comprising the insert fastening means are being removed and particularly when protruding nail ends are being severed after 85 the form has been removed.

My invention contemplates the provision of a simple retaining device which may extend into the interior of the insert and engage the walls thereof and which may be

readily attached to the concrete form separately of any attaching of the insert to the form. As shown in Figs. 1 and 2, a very simple form of my invention may comprise 5 a strip of metal having an intermediate looped portion 16 formed to engage the side walls 11 of the insert, the ends 17 of this strip being perforated whereby the strip may be nailed to the form and the insert subsequently placed in engagement therewith. In this form of retaining means the 10 loop portion 16 of course extends into the insert at the end to which the ribs 14 do not extend.

15 In Figs. 3 and 4 I show the retaining means as comprising simply a staple member 20 with the ends 21 thereof driven into the form B. In this instance the retaining means is completely covered by the insert 20 when the latter is placed in engagement therewith and the insert may rest, around the entire perimeter thereof, adjacent the open side, in contact with the form B.

25 In Figs. 5 and 6, I show a preferred form 30 of my invention which comprises a bent metal strip formed to engage the end walls 12 of the insert and to extend therein a substantial distance whereby the side edges of the strip may engage the ribs 13 and 14 35 and exert a stabilizing influence upon the insert once the latter is placed in engagement therewith. In this form as in the first form the ends of the metal strip are provided with perforations 22 and 23 whereby the strip may be nailed to the form B when not in engagement with the insert, as shown in Fig. 6.

40 I find that the particular shape of the retaining strap illustrated in Fig. 6 involves only a minimum production cost, 45 serves very well in engaging and maintaining the insert when once positioned thereon. This retaining member may be provided with a sub-loop 24 which affords sufficient 50 spring to the end portions 25 to permit manufacturing of the strip of a relatively inexpensive steel having low resilient qualities. As shown in Fig. 5, one leg of the member 55 may be wider than the other whereby this leg may engage the edges of the side walls 11 of the insert and also engage the under surface of the lugs 13. The other leg and spring loop portion 24 may be of a width corresponding to the space between the bolt 60 head retaining ribs whereby the horizontal surfaces of both sets of ribs may be engaged thereby. The leg portions, of course, may be formed to engage a considerable surface of the tapering end walls 12, the looped portion 65 24 serving to permit its legs to be drawn slightly toward each other when the open edge of the insert is being passed thereover and thereafter to cause the legs to spring apart and into firm engagement with the insert end walls.

This particular form of my invention will retain the insert when once positioned thereon during any vibration of the form incident to the construction of concrete form buildings and is quite effective in preventing any 70 displacement of the insert when the concrete is being placed in the form.

From the foregoing description of my invention it will be seen that while extremely simple in character from a manufacturing 75 view point, its use nevertheless permits an accurate locating of the inserts and also a ready removal of the forms without necessitating the expenditure of further labor in trimming projecting nail points, etc.

80 Furthermore it will be understood that my invention is adaptable to the retention of inserts of a type other than I herein disclose.

85 I claim—

1. In combination, a concrete form and resilient means secured to the form and adapted to engage an insert and to maintain it in position whereby concrete may be placed in the form about the insert and said means and the form eventually removed from the said concrete and insert without marring the concrete.

2. In combination, a concrete form and resilient means adapted to be attached to the form independently of an insert and over which the insert may be placed whereby the concrete form may be removed carrying the insert positioning means with it.

3. In a concrete form the combination of 100 a metallic strip formed to extend into the interior of a hollow insert and snugly engage walls thereof, said strip having the ends thereof adapted to be secured to a member of the form, with the intermediate portions contractible whereby the insert may be slipped over the strip and be retained thereby.

4. In combination a concrete form and 110 resilient means secured to the form and adapted to engage the inner surfaces of the walls of a hollow insert and adapted to maintain it in position whereby concrete may be placed in the form about the insert and said means and form eventually removed from the said concrete and insert without marring the concrete.

5. In combination a concrete form, and a resilient metal strip adapted to engage a hollow insert and to be secured to the form at a position at which it is desired to locate the insert and formed to engage the insert to maintain it in proper position when the concrete is being placed in the form.

6. In combination a concrete form, and a resilient metallic strip formed to engage a hollow insert and to be attached to the form separately of the insert and to engage the walls of the insert whereby it may be subsequently attached.

7. In a concrete form the combination of a substantially hollow insert, a metallic strip formed to extend into the interior of the insert and snugly engage walls thereof, said strip having the ends thereof adapted to be permanently secured to a member of the form with the intermediate portions con-

tractile whereby the strip is unattached to concrete when set in the form and detachably connected to the insert.

10

In testimony whereof, I hereunto affix my signature.

JOSEPH HIRSHSTEIN.
